UNITED STATES PATENT OFFICE.

NELSON W. DINGWALL AND CLIFFORD M. BUDD, OF NEW YORK, N. Y.

ADAPTER AND BOOSTER CASING FOR SHELLS.

1,296,169.

Specification of Letters Patent.

Patented Mar. 4, 1919.

Application filed July 26, 1918. Serial No. 246,896.

To all whom it may concern:

Be it known that we, NELSON W. DINGWALL and CLIFFORD M. BUDD, citizens of the United States, residing at New York, in the county of New York and State of New York, have invented new and useful Improvements in Adapter and Booster Casings for Shells, of which the following is a specification.

This invention relates to shells or projectiles and has particular reference to an adapter and booster casing therefor.

It is the purpose of the present invention to provide an adapter and booster casing for shells which comprises a minimum number of parts and is simple in structure, so that the number of operations necessary in manufacturing the structure is relatively small and therefore the rate of production can be increased and the cost of making very materially decreased. The adapter and booster casing are made integral with each other, so that the expense and waste in performing certain operations to connect these parts when they are made separately, as is now usual, are entirely eliminated, and since, in our new structure, there are no joints between the adapter and booster casing, the gas within a gas shell cannot escape into the adapter and then pass from the head and constitute a source of danger to persons handling the shell. The internal bore of the adapter and the chamber of the booster casing are of like diameter throughout their lengths and are provided with a single screw thread for the reception of both the fuse socket holder and the threaded nipple of the fuse body, and thus the operations of counter boring the adapter and making a separate fuse bushing for maintaining the fuse holder in place, and which operations are necessary in making adapters and booster casings as heretofore constructed, are done away with. The operation of filling the booster casing of our structure with an explosive charge can be readily carried out.

The above and other objects of our invention are obtained in the structure described in the following specification and illustrated in the accompanying drawings, and wherein:

Figure 1 is a longitudinal sectional view through our improved adapter and booster casing, the fuse body and a portion of the shell being shown in dotted lines.

Fig. 2 is a sectional view taken on line 2—2 of Fig. 1.

Fig. 3 is an enlarged sectional view of the fuse socket and holder therefor.

In said drawings, the numeral 10 designates the adapter, which is externally threaded as at 11, so as to be screwed into the threaded opening in the nose of the shell or projectile 12. In the present instance we have shown the thread 11 as being in the form of a tapering pipe thread, and while such a thread is of particular utility in the event the adapter is used in connection with a shell containing gas so as to prevent the leakage of gas from the shell, it is, of course, understood that this thread may be varied, as desired, and in cases where the shell contains a high explosive instead of a gas, the threaded portion of the adapter may be cylindrical in shape. For the purpose of screwing the adapter into place, spanner wrench receiving holes 13 are provided in the outer end thereof, but if desired, these may be omitted and the periphery of the adapter outside of the screw threads 11 may be polygonal, so as to provide wrench receiving faces. The bore 14 of the adapter 10 is of uniform diameter throughout its length and is of the same diameter as the external diameter of the nipple 15 of the fuse body 16 and is threaded to directly receive the nipple so that the use of the bushing which is now usually employed between the adapter and the nipple of the fuse, is eliminated.

Formed integrally with the adapter 10 is a booster casing 17. The booster casing 17 is cylindrical in cross section and is closed at its lower end, as is usual, but in the present instance the diameter of the chamber 18 of the booster casing is of like diameter as the uniform bore 14 of the adapter, so that the chamber 18 and the bore 14 form, in effect a single chamber which is devoid of shoulders or the like. The diameter of the bore 14 and, therefore, the diameter of the chamber 18 will depend upon the size of the threaded nipple of the fuse body 16.

The thread 19 of the bore of the adapter extends for some distance downwardly into the chamber 18, so that the fuse socket holder, which in the present instance consists of an externally threaded ring 20, may be screwed into place, it being understood that the nipple 15 and the ring 20 are of the same external diameter and are similarly threaded. The fuse socket, which is designated by the numeral 21, comprises a thimble-shaped member, formed by pressing

or drawing a sheet of thin metal to the proper shape. The fuse socket holder 20 is provided with sockets 24 to receive means by which it may be rotated while engaging the 5 thread 19.

Adjacent the open end of the socket 21, the wall is spun outwardly to form a folded flange 23. To secure the socket 21 in place on the holder 20, the open end of the socket 10 is inserted into the opening of the holder until the flange 23 engages the lower face of the latter and then the open end of the socket is bent radially outwardly to form a flange 22 which is pressed against the upper or outer surface of the ring 20.

It will be seen from the foregoing description that since the adapter 10 and the booster casing 17 are integral with each other, the operations employed in joining 20 the casing and adapter together, where these parts are made separately, are entirely eliminated, so that the cost of manufacture is greatly decreased, and at the same time, since there are no joints between the adapter 25 and the booster casing, all likelihood of the gas escaping is eliminated. As the bore 14 of the adapter and the chamber 18 of the booster casing are of the same diameter and the bore 14 is threaded to directly receive the fuse nipple 15 and also the fuse socket holder, the structure is further simplified.

It is obvious that our invention is susceptible of various modifications and 35 changes which would be within the spirit of the invention without departing from the scope of the following claims.

What we claim is:

1. In combination an adapter provided 40 with means for attachment to a shell and having an extension constituting a booster casing, the interior diameter of which is the same as that of the bore of the adapter, the inner face of the wall of the adapter 45 being provided with a thread that extends continuously from the outer end of the adapter to beyond the open end of the booster casing, a fuse socket holder engaging said thread, and a fuse body having a 50 threaded nipple screwed into the outer end of the bore of the adapter.

Copies of this patent may be obtained for five cents each, by addressing the "Commissioner of Patents, Washington, D. C."

2. In combination an adapter comprising an interiorly threaded tubular body provided with means for attachment to a shell and having an extension constituting a 55 booster casing, a fuse socket holder having an externally threaded ring-like head engaging the interior thread of the adapter and a thimble-like body extending through said head into the booster casing, and a fuse 60 body having a threaded nipple screwed into the outer end of the bore in the adapter.

3. The combination of a fuse socket having an annular flange about its open end and a second flange about its body, and a ring 65 surrounding the socket between said flanges and provided with a peripheral thread, for the purpose described.

4. A fuse holder comprising a tubular head, provided with means for connecting 70 it to a booster casing, and a thimble shaped member having its open end extending through said head and provided with spaced flanges that fit close against the faces of the head.

5. In combination, a fuse socket having a flange at its open end and also having a circumferential fold spaced from its open end, and a fuse holder comprising a ring 80 surrounding said socket and located between the flange and fold thereof.

6. A fuse socket comprising a thimble-shaped member formed from a sheet of thin metal and having a circumferential flange at its open end and also having spaced from 85 its open end a circumferential fold forming a flange.

7. In combination, a fuse socket comprising a thimble-shaped member formed from a sheet of thin material and having its walls 90 at its open end turned outwardly to form a flange, and also having spaced from its open end a circumferential flange formed by folding out the walls of the socket; and a socket holder having an internal flange-like 95 portion positioned between the flanges of the socket.

In testimony whereof we have hereunto set our hands.

NELSON W. DINGWALL,
CLIFFORD M. BUDD.
